Des. 237,055
Patented Oct. 7, 1975

237,055

PACKAGING CONTAINER FOR THERMOMETER OR SIMILAR ELONGATED ARTICLE

John Pardo, Yonkers, N.Y., assignor to Bio-Medical
Sciences, Inc., Fairfield, N.J.

Filed June 20, 1973, Ser. No. 371,678

Term of patent 14 years

Int. Cl. D9—03

U.S. Cl. D9—237

FIG. 1

FIG. 2

FIG. 3

FIG. 4

FIG. 5

FIG. 6

FIG. 1 is a perspective view of the package container for thermometer or similar elongated article showing my new design;

FIG. 2 is a top plan view thereof;

FIG. 3 is a front elevational view thereof;

FIG. 4 is an end elevational view thereof;

FIG. 5 is an end elevational view thereof; and

FIG. 6 is a bottom plan view thereof.

I claim:

The ornamental design for a packaging container for thermometer or similar elongated article, as shown and described.
